US0D1050031S

(12) **United States Design Patent** (10) **Patent No.:** **US D1,050,031 S**
(45) **Date of Patent:** **** Nov. 5, 2024**

(54) **WIRELESS CHARGER**

(71) Applicant: **Shenzhen Autral Technology Innovation Co., Ltd.**, Shenzhen (CN)

(72) Inventor: **Jiawen Jiang**, Shenzhen (CN)

(73) Assignee: **SHENZHEN AUTRAL TECHNOLOGY**, Shenzhen (CN)

(**) Term: **15 Years**

(21) Appl. No.: **29/900,377**

(22) Filed: **Aug. 21, 2023**

(51) LOC (14) Cl. **13-02**

(52) U.S. Cl.

USPC **D13/108**; D13/107

CLAIM

The ornamental design for a wireless charger as shown and described.

DESCRIPTION

FIG. 1 is a first perspective view of a wireless charger showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the wireless charger where the wireless charger is in a first configuration of use; and, FIG. 10 is a perspective view of the wireless charger where the wireless charger is in a second configuration of use.

The broken lines in the Figures are for the purpose of illustrating portions of the article that form no part of the claimed design.

1 Claim, 10 Drawing Sheets
